UNITED STATES PATENT OFFICE.

EDMUND HOFFMAN, OF BROOKLYN, NEW YORK, ASSIGNOR TO AMERICAN CAN COMPANY, OF NEW YORK, N. Y., A CORPORATION OF NEW JERSEY.

DESIGN FOR A TALCUM-POWDER BOX.

53,071.

Specification for Design.

Patented Mar. 11, 1919.

Application filed October 11, 1916. Serial No. 125,125. Term of patent 14 years.

To all whom it may concern:

Be it known that I, EDMUND HOFFMAN, a citizen of the United States, residing at Brooklyn, in the county of Kings and State of New York, have invented a new, original, and ornamental Design for a Talcum-Powder Box, of which the following is a specification, reference being had to the accompanying drawing, forming a part thereof.

On the drawing,

Figure 1 is a side elevation of a talcum

powder box embodying my present invention;

Fig. 2 is a top plan view, and

Fig. 3 is a bottom plan view thereof.

I claim:

The new, original and ornamental design for a talcum powder box as shown.

EDMUND HOFFMAN.
